UNITED STATES PATENT OFFICE.

LEE A. McCALLA, OF CHICAGO, ILLINOIS.

VENTILATOR.

No. 844,735.

Specification of Letters Patent.

Patented Feb. 19, 1907.

Application filed July 3, 1905. Serial No. 268,130.

To all whom it may concern:

Be it known that I, LEE A. McCALLA, a citizen of the United States, residing at Chicago, in the county of Cook and State of Illinois, have invented new and useful Improvements in Ventilators, of which the following is a full, clear, concise, and exact description, reference being had to the accompanying drawings, forming a part of this specification.

10 My invention relates to improvements in devices for ventilating rooms and other apartments, my object being to provide a device which will admit fresh air to the room and which at the same time will prevent a draft 15 from blowing through the open window.

In the devices of this character which have heretofore been constructed what is known as a "diffusion-box" is provided, which communicates with the outer atmosphere and 20 which also has openings communicating with the room. The air is generally admitted to the diffusion-box through vertical openings and traverses variously-arranged passages into the box and thence passes through an 25 opening in the top of the diffusion-box out into the room. By this construction, while the draft to an extent is prevented, I have found that when the ventilators are opened to their fullest extent they do not prevent a 30 draft in the room and if partially closed do not admit sufficient fresh air to the room to properly ventilate the same.

By my improved construction the air is adapted to enter from the exterior of the 35 room through a horizontally-arranged passage and pass into the diffusion-box, where the current of air is deflected by a draft-breaker extending into the diffusion-box and thence passes upwardly out of the diffusion-box into the room. By this construction I am enabled to get the maximum 40 amount of fresh air into the room without in any manner causing a draft therein.

I have illustrated one form of my invention in the accompanying drawings, in 45 which—

Figure 1 is a front elevation of a window, showing my improved ventilator applied; Fig. 2 is a front elevation of my ventilator. 50 Fig. 3 is a plan view of the same; and Fig. 4 is a sectional view of the same, taken on the line 4-4 of Fig. 2.

In the preferred embodiment of my invention I provide a suitable panel 1, which is 55 adapted to be fitted within the window-frame, preferably beneath the raised window,

as shown in Fig. 1, and upon the outer side of this panel a hood 2 is attached. This hood is adapted to extend the length of an opening 3 formed in the panel, and the lower 60 end of the hood is adapted to lie in a plane substantially adjacent the bottom of the opening. To the under side of the panel a deflector 4 is provided, which extends into the hood and is curved outwardly, as shown, 65 having its upper end lying in a plane slightly above the lower end of the hood 2.

If desired, a screen to prevent dust from entering the hood may be placed across the lower opening thereof in any suitable manner. This screen may extend entirely across 70 the lower opening of the hood or it may extend from the upper end of the deflector 4 to the lower end of the hood.

Upon the inner side of the window a diffusion-box 5 is connected opposite the opening 3 and communicating therewith, which preferably has the upturned side 6 thereof extending up to a point slightly above the top of the opening 3. The space between the 75 side wall 6 and the panel may be closed by a lid or draft-breaker 7, which is in the form of a curved plate pivoted at 8 to the panel 1 and having downwardly-extending side flanges 9 at either end thereof. These flanges when 80 the lid is lowered engage against the sides of the panel and prevent the draft-breaker from being dropped too far. They also, due to 85 their frictional engagement with the sides of the diffusion-box, serve to hold the draft-breaker in any position to which it may be moved. Upon the inner side of the diffusion-box I preferably provide a small spring-catch 10, which is adapted to engage the outer edge of the draft-breaker and hold the 90 same in a raised position when it is desired to close the ventilator. While I have shown this as one means of maintaining the draft-breaker in a raised position, any other desired means may be used—as, for instance, 95 forming an inwardly-extending bead along the upper edge of the diffusion-box, which will engage the edge of the draft-breaker and maintain the same in a raised position.

In operation the ventilator is placed in 105 the window in the position shown in Fig. 1, with the hood 2 extending into the open air and the diffusion-box 5 extending into the room. The draft-breaker is lowered to any desired extent, being shown in the drawings 110 as lowered to its furthest position. The air will enter beneath the hood and be deflected

upwardly by the deflector 4. It will then take a course across the hood through the opening in the panel and striking against the curved draft-breaker 7 will be deflected downwardly, whence it will pass beneath the draft-breaker and up into the room, having been diffused before passing into the room and passing into the room without creating a noticeable draft. It will be noted that by 5 my construction there is no possible direct path for the air to enter into the room; but it must take a circuitous path through the hood and deflector before it enters the room, and even though a strong wind would blow the 10 air will take an upward path along the inner side of the glass of the window and not create any noticeable draft in the room. By providing the draft-breaker in the diffusion-box and also adapting the same to be used as a 15 closure for the opening of the diffusion-box the draft will always be broken no matter to what position the draft-breaker may be moved. By this construction I am enabled to entirely eliminate from the device the use 20 of automatic valves or the use of valves which are delicately balanced and liable to get out of order or become rusty and clogged with dust and dirt, and I am enabled to provide a device which gives maximum ventilation 25 with a minimum draft in the room.

While I have described my device as being used in connection with a panel adapted to be fitted within the window, it will be understood that the same may be attached directly to the window-frame, an opening being cut therein, instead of in a separate panel, or the same may be used in any other position desired without departing from the 30 spirit of my invention.

Having thus described my invention, what I claim as new, and desire to secure by Letters Patent, is—

1. In a ventilator, the combination with a hood, having an opening in the bottom thereof, of means for deflecting the air toward the upper part of said hood, a diffusion-box communicating with said hood, and an adjustable draft-breaker adapted to deflect the air toward the bottom of said diffusion-box.

2. In a ventilator, the combination with a hood, having an opening in the bottom thereof, of a deflector extending into said hood, and adapted to deflect the air toward the top thereof, of a diffusion-box communi-

cating with said hood, and an adjustable draft-breaker extending into said diffusion-box and adapted to deflect the air toward the bottom thereof.

3. In a ventilator, the combination with a hood having an opening in the bottom thereof, of means for deflecting the air toward the upper part of said hood, a diffusion-box communicating with said hood, and a draft-breaker arranged in the path of the entering air to deflect the air toward the bottom of said diffusion-box.

4. In a ventilator, the combination with a hood, having an opening in the bottom thereof, of a deflector extending into said hood and arranged to deflect the air toward the top thereof, of a diffusion-box communicating with said hood, and a draft-breaker extending into said diffusion-box in the path of the air to deflect the air toward the bottom thereof.

5. In a ventilator, the combination with a hood open at the bottom, of a diffusion-box communicating with said hood and open at the top, a draft-breaker arranged in said diffusion-box and extending downwardly therein into the path of the admitted current of air.

6. A ventilator having a hood provided with an opening to the atmosphere and a diffusion-box provided with an opening to the room, a deflector arranged in said hood, and a draft-breaker arranged in said diffusion-box in the path of the air to cause the air to take the path of a reverse curve in passing through said ventilator.

7. In a ventilator, the combination with a diffusion-box having the side thereof, opposite the opening through which the air enters the same, in a plane substantially parallel with the window, of a draft-breaker extending into said box, in the path of the entering air, and in a plane substantially parallel with the window to cause eddy-currents in the entering air which tend to take a path in a plane parallel with the window.

In witness whereof I have hereunto subscribed my name in the presence of two witnesses.

LEE A. McCALLA.
